Attorney.

UNITED STATES PATENT OFFICE

ROBERT E. NEWELL, OF IRWIN, PENNSYLVANIA

VALVE STRUCTURE

Application filed December 2, 1927. Serial No. 237,170.

My invention relates to valve structures, and more particularly to means for controlling the flow of gaseous fuel to burners for water heaters, etc.

5 In gas heaters for water, as in the case of domestic water heaters, it is common practice to provide a main supply of gas to the burner for effecting actual heating of the water and an auxiliary supply of gas for a pilot flame, 10 which will burn continuously or will ignite gas from the main supply each time such main supply is turned on as by a thermostatically-controlled valve. In such devices there is commonly no means for automatically controlling the supply of gas for the 15 pilot flame nor for automatically shutting off the main flow of gas in case the pilot flame should become extinguished. To provide a pilot flame, it is usual to supply a 20 small by-pass for gas from the supply line to the burner, and, due to the very small size of the orifice required, such by-pass frequently becomes clogged, particularly where the gas contains foreign matter.

25 One object of my invention is to provide means for automatically shutting off the supply of all gas to the burner in case the flame or pilot becomes extinguished.

Another object of my invention is to provide 30 means for automatically controlling the supply of gas to the pilot flame, so that such flame may be maintained at a predetermined volume.

Another object of my invention is to provide 35 an improved form of thermostat element that will not oxidize or deteriorate in the intense heat of the burner flame.

Still another object of my invention is to simplify and improve generally the structure 40 and operation of fluid fuel burner devices.

One form which my invention may take is shown in the accompanying drawing, wherein Figure 1 is an elevational view of heating apparatus equipped with my invention; Fig. 45 2 is a sectional view, on an enlarged scale, of one of the control valves of Fig. 1, and Fig. 3 is a perspective view of the protecting sleeve for the thermal element of Fig. 2.

The invention is shown as employed in connection with a domestic water heater struc-

ture comprising a storage tank 4, heating coils 5, a burner 6, and a thermostatically-controlled valve 7 for normally controlling the main flow of gas to the burner in accordance with the temperature of the water within the tank 4. These parts may be of various well-known forms.

My invention resides more especially in the provision of an auxiliary valve control device whereby a supply of gas for a pilot flame is automatically maintained at a predetermined rate, and whereby the gas, both the auxiliary supply for the pilot flame and the main supply, are automatically cut off in case the flames become extinguished. The 65 control apparatus above referred to includes a valve casing 8 having valve seats 9 and 10, with a space or chamber between them, and cover plates or castings 11 and 12. The casing 8 is provided with an inlet 13 through which the main gas supply enters from the thermostatically-controlled valve 7, and with an outlet 14 that communicates with the burner 6. A cover plate 11 is provided with an inlet 15, through which gas for the pilot flame may 70 flow from a supply line 15a that has connection with the main supply line 7a in advance of the thermostat 7.

Valve discs 16 and 17 co-operate with the 75 seats 9 and 10 respectively. The valve disc 80 16 is loosely connected to a stem 18, which stem is slidably supported in a boss 19 of the valve casing 8. The outer end of the stem 18 loosely engages with the valve 17. A spring 85 20 urges the valve 16 to its seat and, acting through the stem 18, urges the valve 17 from its seat. Normally, the valve 16 will be closed and gas for the burner 6 will flow from the primary valve 7, through the inlet 13, past the valve 17, and through the outlet 14. A 90 set screw 16a has threaded engagement with the valve 16, and abuts against the stem 18, so that such valve can be adjusted with respect to the stem and the valve 17.

A thermostatic element 21, which may be 95 in the form of a copper or brass tube, is tapped into the cover plate 12 and extends above the burner 6. A push rod 22 of carbon or other non-expanding material is enclosed within the tube 21, its outer end abutting 100

against a screw plug 23 that is carried by the tube 21, and its inner end extending into a recess in the valve 17. Should the burner flame be extinguished, it will be seen that the tube 21 will cool and shrink, thus drawing the rod 22 inwardly and pushing the valve 17 to its seat, thereby shutting off entirely the flow of gas to the burner.

In cases where the main supply of gas from the valve 17 is reduced below the predetermined volume for the pilot flame, the temperature of the thermostat tube 21 will, of course, be reduced, causing it to contract to such an extent as to move the valve 16 from its seat, thereby admitting sufficient gas past the valves 16 and 17 to maintain a normal pilot flame. Should the flame in the burner 6 become completely extinguished, the tube 21 will shrink to such extent as to completely close the valve 17, shutting off flow of gas both from the primary valve 7 and the pilot control valve 16. In order to again establish flow of gas to the burner, a lighted match will first be applied to the tube 21, causing it to quickly expand and allow the valve 17 to open under pressure of the spring 20, for the passage of gas which will be ignited by the match.

A snug-fitting sleeve 25 is provided around the tube 21, for the purpose of sealing it off from the air and consequently preventing oxidization thereof, through contact with the burner flame. This sleeve may be of chromium steel, which will resist oxidization say up to 2000° F., or may be of various other suitable materials. The sleeve is thin enough to readily transmit heat to the copper tube, and may be removed and replaced by taking off the cap 23 and sliding the sleeve off the tube 21, if the cap 23 is of considerably greater diameter than the tube. However, if the cap is of small diameter, as shown in Fig. 2, the sleeve 25 can be slid off without disturbing the cap and, consequently, the setting of the thermostat—that is without disturbing the relative positions of the tube 21 and the rod 22, with consequent variation in adjustment of the valves 16 and 17 relative to the tube 21. Due to its relatively low coefficient of expansion, it is split its entire length to spring or yield so it will not bind on the tube 21 and prevent the normal expansion or contraction thereof.

If the thermostat 7 is a snap-acting or quick-acting one, which suddenly shuts off all gas to the main burner flame, it will be necessary to use an independent pilot burner which remains lighted, and to place the element 22 within a zone affected by the pilot flame but little affected by the main burner flame.

Otherwise, the sudden extinguishing of the main burner would cause the pilot to go out also, as the element 22 would not have time to cool sufficiently to open the valve disc 16.

I claim as my invention:

1. The combination with a fuel burner, of means for controlling supply of fuel thereto, comprising a valve casing having a main inlet, an auxiliary inlet and an outlet, a main valve controlling flow from the main inlet to said outlet, an auxiliary valve for controlling flow from the auxiliary inlet past the said main valve and to the said outlet, and a thermostatic member acted upon by the flame of said burner and having connections with said main and auxiliary valves to cause the auxiliary valve to be moved from its seat upon slight contraction of the thermostat, and to cause the main valve to be moved to its seat upon further contraction thereof. 80

2. The combination with a fuel burner, of means for controlling fuel supplied thereto, comprising a main valve for controlling the main supply of fuel to the burner, an auxiliary valve for controlling flow of fuel for a pilot flame, a thermostatic device acted upon by the burner flame, and means effective upon movement of said thermostatic device in one direction for imparting opening movement to the auxiliary valve and effective upon further movement of said device to effect closure of the main valve. 90

3. The combination with a fuel burner, of a main source of fuel supply therefor, an auxiliary source of fuel supply for a pilot flame, and thermostatic means acted upon by the burner flame and operable upon movement in one direction for admitting fuel from the auxiliary source and upon further movement in said direction to shut off the supply of fuel from both of said sources. 100

4. The combination with a fuel gurner, of a main source of fuel supply therefor, an auxiliary source of fuel supply for a pilot flame, and thermostatic means acted upon by the burner flame and operable upon movement in one direction for admitting fuel from the auxiliary source and upon further movement in said direction to shut off the supply of fuel from both of said sources, the said thermostatic device when in its opposite extreme position serving to permit flow of fuel from said main source, to the exclusion of the flow of fuel from the auxiliary source. 110

5. The combination with water heater structure comprising a fuel burner, a water receptacle, a thermostat controlling a main supply of fuel to the burner in accordance with the temperature of the water, and a pilot supply line independent of the thermostat control, of an additional thermostat device actuated directly by temperature changes in the zone of the burner for controlling flow through said line and for shutting off the said main flow of fuel to the burner in the sequence named. 120

6. The combination with a fuel burner, of a main source of fuel supply therefor, an auxiliary source of fuel supply for a pilot flame, 130

and thermostatic means actuated directly by temperature changes in the zone of the burner and operable upon movement in one direction for admitting fuel from the auxiliary source 5 and upon further movement in said direction to shut off the supply of fuel from both of said sources.

In testimony whereof I, the said ROBERT E. NEWELL, have hereunto set my hand.

10 ROBERT E. NEWELL.
